UNITED STATES PATENT OFFICE.

NORMAN H. SOOY, OF KANSAS CITY, MISSOURI.

POWER-TRANSMITTING MECHANISM.

Application filed December 20, 1926. Serial No. 155,819.

My invention relates to improvements in power transmitting mechanisms, of the type employed for transmitting power mechanically from a power station to operating mechanisms, such as pump jacks, of wells in an oil field.

It relates particularly to a novel swing of the type having draft arms disposed at angles to each other and attached to connecting rods for change of direction of the power transmitted.

One of the objects of my invention is to provide a novel swing of the kind described having the draft arms adjustable from an alined position with respect to each other to different angular positions with respect to each other, so that the connecting rods may be disposed parallel with each other or at angles to each other.

A further object of my invention is to provide a novel mechanism of the kind described, which is simple, cheap, durable, not liable to get out of order, which is easily installed and adjusted to desired positions, and which is efficient in operation.

The novel features of my invention are hereinafter fully described and claimed.

In the accompanying drawing, which illustrates the preferred embodiment of my invention,

Fig. 1 is a plan view of my improved power transmitting mechanism.

Fig. 2 is a vertical section on the line 2—2 of Fig. 1.

Similar reference characters designate similar parts in the different views.

1 designates a vertical post, preferably tubular, mounted in and projecting above a suitable base 2, which may be concrete.

Supporting means are provided, which may be two members 3 and 4 mounted against one side of the post 1, one above the other.

The members 3 and 4 are respectively fastened to the post 1 by two U-bolts 5 and 6 respectively which embrace the post 1 and are provided with nuts 7 respectively bearing against the members 3 and 4.

Oscillative bearing means are provided comprising, preferably, a body 8, the upper and lower ends of which are respectively pivotally mounted in a hole through the member 3 and a recess in the upper side of the member 4.

The bearing means includes a radial arm, which may comprise two parallel channel

bars 9 and 10 disposed one above the other and which are pivotally fastened to the upper and lower sides of the body 8 by a bolt 11 having a nut 12.

Two draft arms are pivotally connected with the body 8 so as to be swung from an alined position, shown in solid lines in Fig. 1, to different angles with respect to each other as shown in dotted lines in Fig. 1.

Each of said draft arms may comprise two channel parallel bars 13 and 14 disposed one above the other and fastened respectively to the upper and lower sides of the body 8 by a vertical bolt 15 having a nut 16.

Between the outer end portions of each pair of bars 13 and 14 is mounted a draft plate 17 to which is pivotally connected a draft link 18 to which a power transmitting connecting bar, not shown, may be attached. Each plate 17 has extending through it a bolt 19 having on it a nut 20, and which is mounted in either of two vertical holes 21 provided in each bar 13 and 14.

Two brace bars 22 are respectively mounted between each pair of draft arm bars 13 and 14. Two vertical bolts 23 having nuts 24 extend respectively through the two pair of bars 13 and 14 and through the bars 22. Each of the bars 22 are provided with a longitudinal row of transverse holes 25 through any one of which is adapted to be extended vertical bolts 26 having a nut 27 and extending through the radial arm bars 9 and 10 adjacent to the outer ends thereof.

By removing the bolt 26, the draft arms may be swung from the alined position, shown in solid lines in Fig. 1, to different relative angular positions, one of which is shown in dotted lines in Fig. 1, after which the draft arms are held in their adjusted positions by inserting the bolt 26 through the radial arm and through the adjacent holes 25 of the bars 22.

For lubricating the bearing means and supporting means therefor, the body 8 has extending vertically through it an axial hole, which at its lower end communicates with the recess in the upper side of the member 4. Mounted in and extending through said hole is a bolt 28 on which is mounted an oil cup 29, which rests upon the upper end of the body 8, and upon the upper side of which bears a nut 30 mounted on the bolt 28. The bottom of the oil cup 29 is provided with a discharge opening 31.

through which oil is discharged upon the upper end of the body 8 from which it flows upon the outer side of said body and inside of the member 3, some of the oil so discharged passing downwardly alongside of the bolt 28 into the recess in the upper side of the member 4.

The members 3 and 4 may be held spaced apart by two shouldered bolts 32, which extend through the members 3 and 4 and upon the upper and lower ends of each of which are respectively mounted nuts 33.

Where the two connecting rods, not shown, which are fastened to the draft links 18 respectively, are to be disposed parallel with each other, the two draft arms 13—14 are disposed in the alined position shown in solid lines in Fig. 1, with the brace bars 22 fastened to the radial arm 9—10 as shown in solid lines in Fig. 1.

When the draft arms are to be disposed at angles to each other, as shown in dotted lines in Fig. 1, the brace bars 22 are fastened to the radial arm as shown in dotted lines in Fig. 1, the disposition of the draft arms being such that the connecting rods, not shown, will be respectively at right angles to said arms.

I do not limit my invention to the structure shown and described, as many modifications, within the scope of the appended claims may be made without departing from the spirit of my invention.

What I claim is.

35 1. In a power transmitting mechanism of the kind described, two draft arms, oscillative bearing means supporting said draft arms and on which the draft arms are adjustable to different angles with respect to each other, said bearing means having a radial arm intermediate of said draft arms, and means connecting said draft arms with said intermediate arm for holding the draft arms in the relative angular positions to which they may be adjusted.

50 2. In a power transmitting mechanism of the kind described, two draft arms, oscillative bearing means supporting said draft arms and on which the draft arms are adjustable to different angles to each other, said bearing means comprising an oscillative body, and a radial arm pivoted to the body and disposed intermediate of said draft arms, and means connecting said draft arms with said intermediate arm for holding the draft arms in the relative angular positions to which they may be adjusted.

55 3. In a power transmitting mechanism of the kind described, two draft arms, oscillative bearing means to which said arms are pivoted so as to be adjustable to different angles with respect to each other, said bearing means having a radial arm intermediate of said draft arms, and means connecting said radial arm with said draft arms by

which the latter are held in the relative angular positions to which they may be adjusted.

4. In a power transmitting mechanism of the kind described, two draft arms, oscillative bearing means comprising an oscillative body and a radial arm pivoted to said body on an axis parallel with the axis of the body and disposed intermediate of said draft arms, said draft arms being pivoted to said body on axes parallel with the axis of the body, and means connecting said radial arm with said draft arms by which the latter are held in the relative angular positions to which they are adapted to be adjusted on said body.

5. In a power transmitting mechanism of the kind described, two draft arms, oscillative bearing means on which said draft arms are adjustable independently to different angles with respect to each other, said bearing means having a radial arm intermediate of said draft arms, and two members respectively fastened to said draft arms and having means for being adjustably fastened to said radial arm for holding the draft arms in the relative angular positions to which they are adjusted.

6. In a power transmitting mechanism of the kind described, two draft arms, oscillative bearing means on which said draft arms are adjustable independently of each other to different angular positions with respect to each other, said bearing means having a radial arm intermediate of said draft arms, and two bars respectively attached to said draft arms and having each a longitudinal row of transverse holes adapted to receive a securing device carried by said radial arm.

7. In a power transmitting mechanism of the kind described, two draft arms, oscillative bearing means having a radial arm, said draft arms being independently pivoted to said bearing means on axes parallel with the axis of said bearing means, two bars respectively pivoted to said draft arms and having each a longitudinal row of transverse holes, and a bolt carried by said radial arm and adapted to enter any one of said holes.

8. In a power transmitting mechanism of the kind described, a post, supporting means carried by the post, bearing means oscillative on said supporting means and having a radial arm, two draft arms pivoted to said bearing means so as to be adjustable to different angles with respect to each other, and means connecting said draft arms with said radial arm for holding the draft arms in the relative angular positions to which they may be adjusted.

9. In a power transmitting mechanism of the kind described, oscillative bearing means having a radial arm, two draft arms adjustable on said bearing means from a position in alinement with each other to differ-

ent angles with respect to each other, and means connecting said draft arms with said radial arm for holding the draft arms in the different positions with respect to each other to which they may be adjusted.

10. In a power transmitting mechanism of the kind described, oscillative bearing means having a radial arm, two draft arms pivoted to said bearing means so as to be adjusted 10 from a position in alinement with each other to different angles with respect to each other, two bars connecting said draft arms respectively with said radial arm, and means for fastening each of said bars at different 15 points to said radial arm.

11. In a power transmitting mechanism of the kind described, a post, supporting means fastened to said post, bearing means oscillative on said supporting means having a radial arm, two draft arms pivoted to said bearing means, two bars respectively fastened to said draft arms, each bar having a longitudinal row of holes, and a securing device carried by said radial arm and adapted to be inserted in any one of said holes 20 of each of said bars.

In testimony whereof I have signed my name to this specification.

NORMAN H. SOOY.
